SPIRAL DRAIN SMOKE WASHER

Filed July 3, 1928

Fig. 1.

Fig. 2.

UNITED STATES PATENT OFFICE

ALBERT A. McCANDLESS, OF NEW YORK, N. Y., ASSIGNOR TO CHARLES M. GERHOLD,
OF NEW YORK, N. Y.

SPIRAL-DRAIN SMOKE WASHER

Application filed July 3, 1928. Serial No. 290,244.

The invention relates to improvements in smoke hydrating and washing apparatus and has particular reference to a structure designed for application to any form or type 5 of chimney and adapted to hydrate and eliminate from the smoke all poisonous fumes, sparks, cinders, soot and gases to clarify such smoke and thusly obviate nuisance in congested civic centers.

10 The object of the invention is in the providing of a supporting super-structure arranged for attachment to the usual forms of chimney walls and peripheral rim bodies, having formed therewith a circular and 15 spirally formed reservoir, supporting thereon a dome and smoke deflector means, said reservoir having mounted therein a water supply coil provided with a series of apertures through which water is forced under 20 pressure in the form of a doubly deflected spray at a point adjacent the under outlet edge of said dome to cause the smoke and all its substances to pass through said spray, to wash thoroughly and hydrate same after 25 which it passes to atmosphere. Another object of the invention resides in the providing of a weather vane or spray deflector means arranged to control the direction of the forced spray of water with relation to the 30 direction of the wind, this object obviates the faulty feature of blowing sprays under high wind conditions.

In the following I describe a general embodiment of the invention, the particular 35 features thereof being more clearly defined hereinafter in the claims.

In the drawing Fig. 1 is a vertical sectional view of a chimney top showing the relative 40 position thereon of the smoke hydrating apparatus all of that structure being shown in full vertical sectional form; and Fig. 2 is a plan cross sectional view of the device constituting the smoke washer taken on the line 2-2 of Fig. 1.

45 Similar numerals of reference indicate similar parts throughout the several views.

In the illustrations forming part hereof 1 designates a chimney top of the usual sheet metal form having a peripheral rim 2, to receive 50 a supporting member 3 cylindrical in

form carrying a channel bead 4 for rigid attachment to said peripheral rim 2 of chimney 1. Sleeve or member 3 has mounted thereon reservoir 5 the bottom of which is diagonally inclined at its bottom in the form of a spiral 55 basin or helically disposed gutter, the upper edge thereof being formed in a supporting rim 6 and having a plurality of holes therein to receive supporting bolts 7 carried by flange 8 forming part of the deflector dome 9. Said 60 dome 9 is conically crowned to deflect the smoke and gases from chimney 1, to force same downwardly toward basin 5.

Said basin 5 or reservoir has mounted 65 therein circular water pipe connection 10 provided with a series of apertures 11 to receive water from feed pipe connection 12 and said basin 5 has connected therewith at its lowest point an outlet or exhaust pipe connection 13 through which the exhaust waters and all 70 foreign substances pass to a suitable point of deposit or reclamation.

Dome 9 has mounted therein a supporting frame 14 provided with a bearing 15 in which is mounted a rotating spindle 16 carrying at 75 its upper end a weather vane or wind guide 17, the lower end of said spindle 16 thereof having mounted thereon an arm 18 carrying levers 19 and supporting on their ends curved plates 20 set normally adjacent spray pipe 80 10 to prevent the spread of the water spray in the face of a high wind at the chimney top, and to control such hydrating sprays regardless of wind direction or velocity.

It is obvious that the structural conditions 85 effected in this assembly may be varied in many ways without departing from the spirit of the invention.

What is claimed and desired secured by Letters Patent of the United States is:— 90

1. A device of the character described comprising a structure mounted on and within the exhaust end of a chimney, a spiral water trough mounted on said structure, a smoke deflector dome mounted on said trough, a 95 water supply head composed of two circular tubes provided with spray apertures disposed in said trough arranged to project an up spray of water in the path of smoke emitted from said chimney and directed in the path 100

of said water spray by said dome, and water pipe connections mounted in said trough arranged to exhaust said trough of the used water and foreign substance collected thereby.

- 5 2. A device of the character described comprising a smoke duct mounted on and within the exhaust end of a chimney, a spiral water receiving reservoir mounted thereon, a smoke deflector dome disposed across the exhaust end of said smoke duct and mounted upon and attached to said reservoir, a water head composed of two circularly arranged pipes having formed therein a multiplicity of apertures adapted to form a water spray between said water head and the peripheral edge of said dome directly in the path of smoke emitted by said smoke duct and deflected therefrom by said dome, and exhaust water pipes disposed in said duct and communicating with said reservoir arranged to exhaust the used water therefrom.
